UNITED STATES PATENT OFFICE.

CHARLES ZECK, OF DETROIT, MICHIGAN.

DESIGN FOR A MATCH SAFE.

Application filed June 9, 1922. Serial No. 2,597. Term of patent 14 years.

To all whom it may concern:

Be it known that I, CHARLES ZECK, a citizen of the United States, residing at Detroit, in the county of Wayne and State of Michigan, have invented a new, original, and ornamental Design for Match Safes, of which the following is a specification, reference being had to the accompanying drawing, forming part thereof.

In the drawing, Figs. 1 and 2 are perspective views of a match safe embodying the present design taken from the front and rear respectively.

I claim:

The ornamental design for a match safe as shown.

CHARLES ZECK.
